US00D731454S

(12) United States Design Patent
Behling

(10) Patent No.: US D731,454 S
(45) Date of Patent: * Jun. 9, 2015

(54) MOBILE PHONE

(71) Applicant: LVMH Swiss Manufactures SA, La Chaux-de-Fonds (CH)

(72) Inventor: Christoph Behling, London (GB)

(73) Assignee: LVMH Swiss Manufactures SA, La Chaux-de-Fonds (CH)

() Term: 14 Years

(21) Appl. No.: 29/469,800

(22) Filed: Oct. 15, 2013

(30) Foreign Application Priority Data

Apr. 23, 2013 (CH) 734820201

(51) LOC (10) Cl. 14-03

(52) U.S. Cl.

USPC ..... D14/138 AA; D14/345

(57) CLAIM

The ornamental design for a mobile phone, as shown and described.

DESCRIPTION

FIG. 1 illustrates a perspective view of a mobile phone employing an ornamental design in accordance with the present invention;

FIG. 2 illustrates a front view of the mobile phone of FIG. 1; FIG. 3 illustrates a back view of the mobile phone of FIG. 1; FIG. 4 illustrates a left side view of the mobile phone of FIG. 1;

FIG. 5 illustrates a right side view of the mobile phone of FIG. 1;

FIG. 6 illustrates a top view of the mobile phone of FIG. 1; and,

FIG. 7 illustrates a bottom view of the mobile phone of FIG. 1.

The features that are visible only in the back view of FIG. 3 and not indicated from the side views are substantially flat, with no significant thickness or contour.

1 Claim, 7 Drawing Sheets
